SAFETY FOUNTAIN PEN

Diedrich E. Steven, Chicago, Ill.

Application January 20, 1944, Serial No. 519,018

3 Claims. (Cl. 120—49)

This invention relates to a fountain pen and aims to provide a novel construction capable of being closed or sealed when not in use to avoid leakage or spilling.

It is further aimed to provide a novel structure wherein the feeder bar and pen point will be automatically projected as a cap is removed to expose the same, and also to provide on such cap a depressing element engageable with the feeder to retract the latter as the cap is applied.

The more specific objects and advantages will in part be pointed out and otherwise become apparent from a consideration of the description following taken in connection with accompanying drawing illustrating an operative embodiment.

In said drawing:

Figure 1 is a view in elevation of a fountain pen constructed in accordance with the invention;

Figure 2 is a central longitudinal sectional view through the pen in closed condition;

Figure 3 is a sectional view similar to Figure 2, but with the pen point projected and with the cap in inoperative position;

Figure 4 is a cross section taken on the line 4—4 of Figure 3; and

Figure 5 is a fragmentary central longitudinal sectional view taken through a modified form.

Referring specifically to the drawing wherein like reference characters designate like or similar parts, a tubular barrel is shown at 10 having extension 11 thereon, at one end, such extension being detachable or rigid with the barrel 10 proper, as preferred. Extension 11 has a central longitudinal cylindrical bore at 12 in which a feeder bar 13, for ink from the interior of the barrel 10 to a pen point 14 carried by the feeder bar, passes. The feeder bar 13 may be of any usual or suitable construction and it carries a bushing or sleeve 15 which directly slidably engages bore wall 12.

It will be noted that the feeder bar 13 is spaced from the bore of the bushing 15 as at 16, in order to detachably receive and retain the pen point 14 between them.

Screw threaded at 17 in the other end of the barrel 10 is a thimble or plug 18 in which an elongated tube 19 is slidable, the same being unitary with a cork or other gasket at 20 secured to the tube by flanges 21 extending outwardly from the latter.

An elongated rod 22 extends from the feeder bar 13 into the tube 19 and terminates in a piston-like head 23 engaging the wall of the tube to 55

prevent passage of ink past the same. An expansive coil spring 24 is housed within the tube 19 between the closed end of the latter and the head 23, and is adapted to urge the head 23, rod 22, 5 feeder bar 13 and pen point 14 to the projected or writing position shown in Figure 3.

An end section 25 is adapted to be screw threaded at 26 to the plug 18 in order to cover the adjacent end of the tube 19.

10 A suitable cap is provided at 27 which may be made in sections in order to secure an attaching clip 28 therebetween, as shown. This cap or closure 27 intimately engages the extension 11 along tapered walls as at 29 and the cap has interior screw threads at 30 detachably engaging exterior screw threads 31 on the extension. In addition, a central longitudinal rod 32 projects inwardly from the base of the cap 27, abuts the outer end of the feeder bar 13 and as the cap is screwed in place, the rod 32 displaces the feeder bar 13 at point 14, moving the same inward to the position shown in Figure 2, in which the spring 24 is compressed. In such position, the cap engages the extension 11 in a tight manner 25 guarding against danger of spilling or leakage of ink therefrom.

When the cap 27 is removed, the rod 32 will disengage the feeder bar 13 and hence the expansive action of the spring 24 will extend the 30 feeder bar and pen point as shown in Figure 3, to operative or writing position, after which, the cap 27 may be frictionally and detachably mounted on the free end of the end section 25.

The gasket 20, as stated, may be of cork, but 35 no limitation is to be implied, since it may be made of rubber or any other suitable material. As shown in Figure 5, a rubber gasket 20a is provided which functions exactly like that at 20, being carried by a tube 19a like that at 19, as by 40 means of outwardly extending flanges at 21a. The rod 22a, head 23a and spring 24a are like rod 22, head 23 and spring 24 of the preceding form.

It will be understood that the parts may be 45 made from any suitable material.

Also, in refilling the pen, this end is accomplished by holding the extension 11 in ink and operating the tube 19 in the manner of a pump.

I claim as my invention:

50 1. A pen of the class described having a barrel, means slidably therein to fill the barrel with ink and including a tube, feeder means carrying a pen point slidably mounted in the barrel and extending into the tube, spring means within the tube engageable against the feeder means to urge

projection of the latter to writing position, and cap means applicable to the barrel having a part engageable with the feeder means to move the latter to retracted position as the cap is applied.

2. A pen of the class described having a barrel, means slidable therein to fill the barrel with ink and including a tube, feeder means to carry a pen point slidably mounted in the barrel and extending into the tube, spring means within the tube engageable against the feeder means to urge projection of the latter to writing position, cap means applicable to the barrel having a part engageable with the feeder means to move the latter to retracted position as the cap is applied, a gasket attached to the tube and peripherally engaging the inner wall of the barrel.

3. A pen of the class described having a barrel,

means slidable therein to fill the barrel with ink and including a tube, feeder means to carry a pen point slidably mounted in the barrel and extending into the tube, spring means within the tube engageable against the feeder means to urge projection of the latter to writing position, cap means applicable to the barrel having a part engageable with the feeder means to move the latter to retracted position as the cap is applied, 5 a gasket attached to the tube and peripherally engaging the inner wall of the barrel, a plug attached to the barrel and through which the tube slidably extends, and a rod extending from the 10 feeder means into the barrel, terminating in a head in the latter in engagement with the spring.

DIEDRICH E. STEVEN.
